REFRIGERATING SYSTEM

Filed Nov. 16, 1929

Inventor:
George Hilger,
By Mindelel Parker Atty.

UNITED STATES PATENT OFFICE

GEORGE HILGER, OF CHICAGO, ILLINOIS

REFRIGERATING SYSTEM

Application filed November 16, 1929. Serial No. 407,583.

The present invention relates to improvements in refrigerating systems, and has particular reference to systems of the type disclosed in my copending application, Serial No. 306,563, filed September 17, 1928.

The primary objects of the invention reside in the provision of a new and improved refrigerating system having a plurality of refrigerating units preferably arranged in a substantially vertical stand, in which the liquid head is substantially eliminated, which can operate on relatively low pressures and low pressure differences, in which there is but a slight temperature difference between the units, said units having substantially the same evaporating effect, and in which an exact control is unnecessary.

A more specific object resides in the provision of a novel refrigerating system of the foregoing character in which the refrigerant is carried from each unit to the next by an injector action.

Another object resides in the provision of a new and improved refrigerator system which comprises a plurality of superimposed units rigidly connected in a unitary header, and in which each unit comprises a liquid chamber, and a circulating element opening therefrom and disposed entirely therebelow so as to be flooded constantly.

A further object of the invention is to provide a novel refrigerating system comprising a plurality of superimposed liquid chambers and a plurality of circulating elements for circulating liquid from said chambers through the space to be cooled, in which means is provided for automatically discharging gas and entrained liquid upwardly from one chamber to another, and in which each element discharges to the top of the chamber below the chamber from which it receives liquid, thus effecting a recirculation of the refrigerant.

Other general objects reside in the provision of a novel refrigerator of the foregoing character in which oil in the refrigerant is separated out in the first or lowermost unit, in which the liquid is automatically and uniformly distributed from bottom to top upon starting up from an idle condition, in which a

quick heat transfer is effected, and in which the refrigerant is superheated in the uppermost unit before withdrawal.

Further objects and advantages will become apparent as the description proceeds.

In the accompanying drawing, Figure 1 is a side elevational view of a refrigerating system embodying the features of my invention.

Fig. 2 is an axial sectional view of the header taken along line 2-2 of Fig. 1.

Fig. 3 is an axial sectional view of the header taken along the line 3-3 of Fig. 1.

Fig. 4 is a transverse sectional view taken along line 4-4 of Fig. 2.

Fig. 5 is a transverse sectional view taken along line 5-5 of Fig. 2.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawing, the refrigerating system constituting the exemplary embodiment of the invention comprises a plurality of superimposed refrigerating units, preferably arranged in a substantially vertical stand.

In the present instance, six units are provided, and these units comprise respectively six superimposed chambers 10 to 15. Preferably, the chambers are formed in an integral cylindrical header. To this end, an elongated cylindrical casing 16 closed at the bottom and top by end walls 17 and 18 respectively is provided. Interposed in the casing 16 in parallel spaced relation along its length are a plurality of transverse partition walls 19 to 23 which together with the end walls 17 and 18 serve to define the end walls of the chambers 10 to 15.

The lowermost chamber 10 is the refrigerant inlet or supply chamber, the top chamber 15 is the superheated refrigerant gas take-off chamber, and the intermediate chambers 100

11 to 14 are conveniently designated as liquid refrigerant distribution chambers.

Suitable means is provided for supplying refrigerant from an external source of supply (not shown) to the chamber 10. In the present instance, this means comprises an inlet pipe 24 opening substantially to the top of the chamber 10. The refrigerant usually is available from the source at a relatively high pressure, and is supplied through suitable pressure reducing means (not shown) and supply control means (not shown) to the chamber 10 at a relatively low pressure. At the reduced inlet pressure, the refrigerant is at or near the boiling temperature. Some heat will be abstracted thereby from the gas refrigerant discharged to the chamber 10 from the lowermost circulating element as will be hereinafter described. Hence, the refrigerant will be present in the chamber 10 in both vapor and liquid phases, but the amount of liquid available will be substantially in excess of the evaporation requirements.

The liquid refrigerant will collect in the bottom of the chamber 10, and the vapor will collect in the top. Any oil present in the refrigerant will settle to the very bottom from where it can be withdrawn through a suitable oil drain 25. The chamber 10 thus can also be appropriately designated as the oil separation chamber.

Means is provided for conveying refrigerant from the chamber 10 upwardly successively to each of the other chambers. In the instance of chambers 10 and 11, this means comprises an open ended tube 26 mounted vertically in the partition wall 19. Of the tube 26, the lower end terminates near the top of the chamber 10 but preferably downwardly and slightly below the inlet 24 and the upper or discharge end terminates near the top of the chamber 11 and constitutes the refrigerant inlet means corresponding to the inlet 24 for the chamber 10. Preferably, the lower end of the tube 26 is slotted longitudinally as indicated at 27.

In operation, vapor will pass upwardly from the chamber 10 through the tube 26 to the chamber 11. Since liquid refrigerant in excess of its evaporating capacity is supplied to the chamber 10, the liquid level will rise gradually to or above the inlet end of the tube 26, and as a result, the vapor passing over to the chamber 11 will entrain a liquid mist which will precipitate to the bottom of the chamber. The liquid thus carried over into the chamber 11 also is in excess of the evaporation requirement of that unit, and hence the liquid level will rise therein as in chamber 10.

Similar tubes 26 are provided for conveying gaseous and liquid refrigerant upwardly from one to the other of the chambers 11 to 14. The tubes are staggered laterally to per-

mit the immediate inlet and discharge ends of any two adjacent tubes to extend past each other. The uppermost tube 26 terminates but a short distance above the floor of the chamber 14.

Preferably, the chambers 14 and 15 are substantially smaller in size than the four lowermost chambers. The chamber 14 communicates with the chamber 15 through suitable refrigerant superheating elements as 70 will be hereinafter described. The gaseous refrigerant is withdrawn from the top of the chamber 15 through a suitable discharge pipe 28 leading to a compressor (not shown). It will be understood that the amount of refrigerant which should be supplied to the chamber 10 is determined by the evaporating requirements of the system, and that the supply may be controlled manually or automatically in accordance with the temperature 80 of the gas leaving the chamber 15.

Suitable means is provided for circulating liquid refrigerant from each of chambers 11 to 14 through the space to be cooled. While this means may take various forms, preferably a plurality of suitable circulating coils are provided. I have shown a single coil for each of chambers 11 to 14, but it is to be understood that any desired number of coils in parallel may be provided. Thus, four coils 90 29 to 32 are connected respectively to receive liquid refrigerant from the chambers 11 to 14.

Each of the coils 29 to 32 is disposed entirely below the chamber from which it receives liquid refrigerant. Thus, the coil 29 is connected at its lower and inlet end to a pipe fitting 33 which extends through the side of the casing 16 near the lower end of the chamber 10 and then upwardly through the partition wall 19 to the bottom of the chamber 11, and is connected at its upper and discharge end to a pipe fitting 34 which opens through the casing to the top of the chamber 10. Similar fittings 33 and 34 are provided 100 for connecting the coils 30 to 32 to the proper chambers. Since each circulating coil is disposed entirely below the chamber from which it draws its supply of refrigerant, the liquid in the chamber constitutes a substantial head 105 at all times tending to maintain the coil in flooded condition and to increase the rate of circulation.

As a result, any bubbles of gas tending to collect on the inner surface of the coil are 110 rubbed off thereby keeping the surface wetted, and in general a quick rate of heat transfer is obtained. Due to the substantial head forcing circulation in one direction, danger of backfire and of entrapment of liquid by the 115 sudden formation of gas is eliminated.

The refrigerant that is evaporated in the coils is returned to the chamber below that from which the liquid is received, and joins 120 with the vapor passing to the chamber im- 130

mediately above. Thus, there is a recirculation of the refrigerant. No means for injecting liquid refrigerant from the chamber 14 into the chamber 15 is provided, and but a 5 relatively small head of liquid is maintained in the chamber 14. Opening from the lower end of the chamber 14 at a point somewhat below the discharge end of the tube 26 is a pipe fitting 35 to which is attached the lower 10 and inlet end of an evaporating and superheating coil 36 generally similar in form to the coils 29 to 32.

The upper and discharge end of the coil 36 is connected to a pipe fitting 37 which extends 15 through the casing 16 into the upper part of the chamber 14 and then upwardly through the wall 23 to the floor of the chamber 15. If the liquid level in the chamber 14 rises above the mouth of the fitting 35, 20 the liquid will partly fill the lower leg of the coil 36 and will evaporate therein, and the resultant gas together with other gas from the chamber 14 will pass therethrough to the chamber 15.

25 A fitting 38 opening vertically from the top of the chamber 14 through the wall 23 and then laterally through the casing 16 is connected to the lower inlet end of a second superheating coil 39. The upper discharge 30 end of this coil is connected to a fitting 40 opening through the casing 16 to the top of the chamber 15. Thus, any gaseous refrigerant passing from the chamber 14 to the chamber 15 is superheated before being discharged 35 into the latter. The superheated gas is removed from the chamber 15 to the source.

Preferably, a restricted port 41 is formed in the lower bend of each of the fittings 33 within the casing 16. The ports 41 permit 40 any oil that might be carried from the chamber 10 over into the chambers 11 to 14 to drip back, and also serve to permit all the liquid refrigerant in the system to return to the bottom of the header when the system is at rest.

45 I claim as my invention:—

1. A refrigerating system comprising, in combination, a unit having a space adapted to contain separated liquid and vapor phases of the refrigerant, an inlet line for supplying refrigerant under pressure to said space, an oil drain opening from the bottom of said space, and an outlet line having its inlet disposed at the predetermined normal level of the liquid for discharging vapor or vapor and 55 entrained liquid from said space to a pressure lower than the inlet pressure.

2. A refrigerating system comprising, in combination, a unit having a space adapted to contain separated liquid and vapor phases of the refrigerant, an inlet line for supplying refrigerant under pressure to the top of said space, an oil drain opening from the bottom of said space, and an outlet line having its inlet disposed at the predetermined normal 60 level of the liquid and below the discharge end

of said inlet line for discharging vapor or vapor and entrained liquid from said space to a pressure lower than the inlet pressure.

3. A refrigerating system comprising, in combination, two superimposed chambers 70 adapted to contain separated liquid and vapor phases of the refrigerant, inlet means for supplying refrigerant under pressure to the upper portion of the lowermost chamber, a vertical injector tube opening from the lower chamber at an intermediate point below said inlet means to the upper portion of the uppermost chamber, discharge means opening from the upper portion of said uppermost chamber, and a liquid cooling coil opening 80 from the bottom of said uppermost chamber and discharging to the top of said lowermost chamber.

4. A refrigerating system comprising, in combination, an elongated vertical casing, a plurality of vertically spaced partition walls in said casing dividing the latter into a plurality of vertically spaced liquid refrigerant distributing chambers, means for supplying liquid refrigerant to the upper end of the lowermost chamber, means for withdrawing refrigerant gas from the upper end of the uppermost chamber, a plurality of connecting pipes extending respectively through said walls, one from adjacent the upper end of each chamber to adjacent the upper end of the chamber immediately above and to above the inlet end of the pipe immediately above, and a plurality of liquid circulating coils, one for each chamber excepting the lowermost chamber, each coil opening from the bottom of one of said last mentioned chambers and discharging to the chamber immediately below.

5. A refrigerating system comprising, in combination, a pair of units defining two superimposed chambers each adapted to contain separated liquid and vapor phases of the refrigerant, an injector pipe opening from an intermediate point in the lower chamber 105 to an intermediate point in the upper chamber, and liquid circulating means opening from the lower portion of the upper chamber 110 to the upper portion of the lower chamber.

6. A refrigerating system comprising, in combination, a pair of units defining two superimposed chambers each adapted to contain separated liquid and vapor phases of the refrigerant, an injector pipe opening from an intermediate point in the lower chamber to an intermediate point in the upper chamber, and liquid circulating means opening from the lower portion of the upper chamber to the upper portion of the lower chamber, said means being located entirely below the upper 120 chamber.

7. A refrigerating system comprising, in combination, a pair of vertically spaced chambers, means adapted upon the creation 125 of a lower pressure in said upper chamber 130

than in said lower chamber to convey automatically liquid and gaseous refrigerant from the latter to the former, and cooling means disposed entirely below said upper chamber for circulating liquid therefrom and 5 discharging to said lower chamber.

8. A refrigerating system comprising, in combination, a chamber adapted to contain liquid and vapor phases of the refrigerant, 10 means for supplying refrigerant under pressure to said chamber, means for removing vapor from the top of said chamber to a lower pressure, the inlet of said last mentioned means opening at an intermediate point in said chamber, and a liquid circulating coil opening from the normal liquid space of said chamber, said coil discharging to said first mentioned means.

9. A refrigerating system comprising, in combination, a cylindrical casing, transverse partitions in said casing defining two superimposed chambers, means for supplying refrigerant to the lower chamber, an injector pipe opening through the intermediate partition from an intermediate point in the 25 lower chamber to an intermediate point in the upper chamber, a liquid circulating coil opening from the bottom of the upper chamber through said intermediate partition, then downwardly into the lower chamber, then laterally out of the lower chamber and then through the space to be cooled, and discharging to the top of the lower chamber, and means discharging from the top of the upper chamber.

10. A refrigerating system comprising, in combination, a vertical stand of superimposed chambers, means for supplying liquid refrigerant to the lowermost chamber, injector means for conveying vapor or a mixture of vapor and entrained liquid upwardly from each chamber to the next chamber, means for circulating liquid from each of the chambers above the lowermost chamber 40 through a tortuous path and then discharging to a lower chamber, and means for withdrawing refrigerant from the upper chamber.

11. A refrigerating system comprising, in combination, a vertical cylindrical casing, a plurality of transverse partitions in said casing defining a bottom chamber, a top chamber and a plurality of intermediate chambers, means for supplying liquid refrigerant to the top of said bottom chamber, injector means for conveying vapor or vapor and entrained liquid from each chamber upwardly to the next chamber, said injector means in each instance terminating at an intermediate point in the chamber to which it 50 discharges so as to permit a separation of the liquid and vapor phases of the refrigerant discharged therefrom, a plurality of liquid circulating coils, one for each chamber above the bottom chamber, each coil being located

entirely below its chamber and opening from the bottom thereof and discharging to the chamber immediately below, gas circulating means opening from the top chamber, and means for withdrawing gas from said last 70 mentioned means.

12. A refrigerating system comprising, in combination, three superimposed chambers, means for supplying refrigerant in liquid and vapor form to the lowermost chamber, 75 means for injecting liquid entrained vapor from the lowermost chamber to the intermediate chamber at an intermediate point, means for circulating liquid from the bottom of said intermediate chamber and discharging to the top of said lowermost chamber, a superheating coil opening from said intermediate chamber at a point below the discharge end of said injector means and discharging to the bottom of the uppermost chamber, a second superheating coil opening from the top of said intermediate chamber and discharging to the upper portion of said uppermost chamber, and means for withdrawing the gaseous refrigerant from the 80 uppermost chamber.

13. A refrigerating system comprising, in combination, a refrigerating unit having a space adapted to contain separated liquid and vapor phases of the refrigerant, an inlet line for supplying refrigerant under pressure to said space, an outlet liquid and vapor line having its inlet end opening at the normal level of the liquid in said space, means for maintaining a lower pressure in said outlet line than in said inlet line, and liquid circulating means opening from said space at a point below the normal level of the liquid, 95 said means being disposed below said unit.

In testimony whereof, I have hereunto affixed my signature.

GEORGE HILGER.
